UNITED STATES PATENT OFFICE.

WARREN C. PATTERSON, OF TAMAQUA, PENNSYLVANIA.

METALLIC RAILWAY-TIE.

1,329,205.

Specification of Letters Patent. Patented Jan. 27, 1920.

Application filed September 26, 1919. Serial No. 326,446.

To all whom it may concern:

Be it known that I, WARREN C. PATTERSON, a citizen of the United States, residing at Tamaqua, in the county of Schuylkill and State of Pennsylvania, have invented a new and useful Metallic Railway-Tie, of which the following is a specification.

This invention relates to railway ties, and particularly to metallic railway ties.

10 An object of the invention is to provide a railway tie with downwardly projecting parts for penetrating the earth and preventing any lateral or longitudinal shifting of the rails.

15 A further object is to provide the tie with means whereby the rails may be spiked down in the usual manner by the use of ordinary spikes, thus obviating the necessity for using special bolts or other fastening devices and rendering the railway tie of the present invention strong in its construction, reliable, durable and economical in installation and maintenance.

20 A full and complete understanding of the invention may be obtained from a consideration of the following detailed description, taken in connection with the accompanying drawing forming a part of this specification; it being understood that while the 25 drawing shows a practical form of the invention, the latter is not to be confined to strict conformity therewith, but may be changed or modified, so long as such changes or modifications mark no material departure from the salient features of the invention as specifically pointed out in the 30 claims appended hereto.

35 In the drawing, in which similar reference characters designate corresponding parts throughout the several figures.

40 Figure 1 is a perspective view of the improved metallic railway tie;

Fig. 2 is a bottom plan view of the same;

45 Fig. 3 is a longitudinal sectional view through the tie and showing the rails in position thereon;

Fig. 4 is a transverse sectional view 50 through the tie and showing one of the rails in position thereon;

55 Fig. 5 is a perspective view similar to Fig. 1, showing a slightly modified form of the invention;

Fig. 6 is a longitudinal sectional view of the same;

55 Fig. 7 is a transverse sectional view thereof similar to Fig. 4;

Fig. 8 is a plan view of one end of a tie of another form of construction;

Fig. 9 is a plan view of a tie of still a different form of construction, one end being shown in horizontal section.

One of the principal items in the maintenance of railways is the cost of the ties which, if formed of wood, are constantly requiring replacement by reason of their 60 quickly rotting out, and in the event of their being formed of cement or concrete are so expensive to manufacture as to render their use almost prohibitive. The device of the present invention has been designed 65 with a view to providing a tie having all the advantages of the wooden or the concrete tie and eliminating the disadvantages of the same by the provision of a practically indestructible metallic tie having means for engaging the earth to prevent any movements of the same in any direction, while under strain, and also means whereby the rails may be readily spiked into position in the ordinary manner; and a tie wherein the number of parts is reduced to a minimum; and 70 wherein a plain, smooth surface is presented to the action of the elements and all pockets or crevices which catch and hold water, are eliminated.

75 The tie consists of a sheet of suitable iron or steel or some other specially prepared metal and bent to form a top and side flanges 2-2, formed integrally therewith and extending substantially at right angles 80 thereto along the longitudinal edges thereof. The channel metal comprising the tie is of sufficient strength and thickness to withstand the enormous strain to which railway ties are subjected and may be readily found in stock material as manufactured. The proportions of the tie as to length and width, may be varied to suit the particular road on which they are to be used, it being 85 of course understood that at switches, crossovers, and the like, the length of the tie will have to be increased.

90 The top 1 of the tie is provided with a pair of spaced openings 3-3, preferably, though not necessarily, rectangular in form, 100 and the centers of these openings 3-3 are a distance apart equal to the distance between the centers of the rails of a standard gage road.

95 Metallic boxes 4-4, formed of the same 110 material as the tie preferably, are secured to the underside of the tie, between the de-

pending flanges 2—2 and in surrounding relation to the openings 3—3. These boxes are open at their tops and comprise, each, a bottom 5, side walls 6—6 and end walls 5 7—7, defining a receptacle having dimensions equal to the dimensions of the openings 3—3 in the top plate of the tie.

The side walls 6—6 of the boxes are provided with integral outstanding flanges 10 8—8, extending toward the depending flanges 3—3 of the tie 1, and provided with suitable apertures in registering relations with suitable apertures formed in the top plate 1 adjacent to the corners of the openings 3—3 therein. Rivets or bolts 9, or other suitable fastening devices traversing the said registering apertures of the top plate and the box flanges serve to securely hold the boxes in position upon the under 15 side of the tie, and it will be noted that the depth of the boxes is equal substantially to twice that of the depending flanges of the tie and form decided projections which are adapted to enter the earth a substantial 20 distance beyond the marginal flanges 2—2.

Wooden blocks 9^a—9^a are cut to snugly fit the boxes 4—4 and to rest therein, the top surfaces of the same lying flush with the top surfaces of the said ties, and the rails 30 10—10 are adapted to rest directly upon the tops of the wooden blocks 9^a—9^a and the adjacent portions of the tie, and to be spiked to said blocks as by ordinary spikes 11—11 in the usual manner. In this manner, the 35 use of bolts or other expensive and complicated fastening means is avoided, and it will be seen that the rails have a solid bed to rest upon, the upper heads of the rivets or bolts 9 being countersunk to lie flush 40 with the top surface of the tie so as not to interfere with the flanges of the said rails.

In Figs. 5, 6 and 7, there is illustrated a slightly modified form of the invention wherein the large openings 3—3 are eliminated and a pair of spaced rectangular openings 3^a are employed for the passage of the spikes 11. These openings are preferably of a size to admit the shank of the spike and to exclude water from the wooden block 9^a 45 contained within the box 4 in the same manner as the previously described form of the invention, and the said openings 3^a are arranged in different longitudinal lines with relation to the tie, so as to avoid splitting the wooden block 9^a when the spikes are 50 driven home.

In Fig. 8 an arrangement is shown wherein in a pair of spiked openings 3^a are provided to lie at each side of a rail and in 55 position to securely hold the latter to the tie 1.

In place of the wooden blocks located within the boxes 4—4, concrete or cement blocks 9^b may be used, as shown in Fig. 9, 60 in which event the latter may be poured

into the boxes in a plastic condition, and headed bolts 11^a placed in position during the process having their upper threaded ends extending through suitable apertures in the tie 1, and beyond the top surface of 70 the same the proper distance apart to receive the flanges of the rails, as will be understood. Suitable nuts may then be screwed upon the threaded upper ends of the bolts and clamped down upon the said 75 rail flanges to securely bind the rail in position upon the tie.

The concrete filler 9^b may be used with either form of the invention, as the same may be readily poured into the box 4 of the 80 form shown in Figs. 1—4, through the openings 3—3 and allowed to harden with the aforementioned headed bolts in position, whereas, in the case of the forms shown in Figs. 5 to 9 inclusive the concrete filler 9^b 85 is formed in the box 4 before the same is secured in position upon the under side of the tie 1 by means of the rivets 9.

From the foregoing it will be seen that an extremely simple, durable and cheaply 90 manufactured railway tie has been provided which may be handled and installed in the same manner as the ordinary wooden tie, and which, by reason of its composition, will not sag, rot or warp, and, having means 95 for penetrating the earth, may not slue or creep while under the pressure of passing trains, the side flanges of the tie effectually preventing any movement of the latter in the direction of the line of travel and the 100 depending boxes likewise holding the tie immovable in a transverse direction.

What is claimed is:—

1. A metallic railway tie, comprising a top plate having integral, marginal flanges 105 depending from its longitudinal edges and having openings formed therein adjacent to its ends, and open-top boxes secured beneath the openings upon the underside of the tie and comprising bottoms, end walls 110 and side walls carrying outwardly extending flanges for attachment to the tie between the flanges thereof, said boxes being of greater depth than said flanges.

2. A railway tie comprising a metallic 115 base member having integral, depending marginal flanges along its long side edges, said base member having openings adjacent to its ends and spaced apart a distance equal to the distance between the rails, metallic 120 boxes secured to the underside of the base member between the depending flanges thereof, and below said openings, said boxes being of greater depth than said flanges, and blocks fitted within the said boxes and constituting a foundation for the spikes.

3. A metallic railway tie, comprising a top plate having longitudinal marginal flanges formed integrally therewith and having spaced openings formed therein ad- 130

5 jacent to its ends, metallic boxes corresponding to the shape of the said openings and adapted to be carried upon the underside of the tie, said boxes comprising bottoms, end walls and side walls, the side walls carrying integral outstanding flanges extending toward the depending flanges of the top plate, means for securing the outstanding flanges thereto, and blocks fitted 10 within the said boxes and adapted to lie with their upper surfaces flush with the upper surface of the tie so as to support the

15 rail and to receive the fastening means for holding the same, said boxes extending down below the side flanges of the tie and adapted to penetrate the earth for preventing movement of the tie thereon.

In testimony that I claim the foregoing as my own, I have hereto affixed my signature.

WARREN C. PATTERSON.
